UNITED STATES PATENT OFFICE.

MICHAEL H. RYAN, OF SAN BERNARDINO, CALIFORNIA, ASSIGNOR OF ONE-TENTH TO
JULIUS J. PEYRON, OF SAN BERNARDINO, CALIFORNIA.

AIR-BRAKE DETAIL.

1,418,400.

Specification of Letters Patent. Patented June 6, 1922.

Application filed December 9, 1920. Serial No. 429,443.

To all whom it may concern:

Be it known that I, MICHAEL H. RYAN, a citizen of the United States, residing at San Bernardino, in the county of San Bernardino and State of California, have invented a new and useful Air-Brake Detail, of which the following is a specification.

By way of explanation it may be stated that there are several conditions under which 10 the quick-action triple valve of an automatic air brake may be made to assume the undesired emergency position. The first and most prevalent cause is a dirty valve, giving rise to undue friction, the result being 15 that the valve does not respond to light reductions, but hangs back, in released position, until the difference in brake pipe and auxiliary pressure is so great that, when the triple valve does respond, it moves so 20 rapidly that there is no time for auxiliary air to pass to the brake cylinder. The slide valve reaches service position and the triple valve is forced forward at once, compressing its graduating spring, and assuming emergency 25 position. All of the other triple valves almost invariably are applied, the result being serious damage to cars and their contents. An undesired emergency application may occur from defects in the triple valve, 30 for instance, a broken graduating pin or a weak or broken graduating spring.

The foregoing being true, one object of this invention is to provide a simple valve which, being interposed between the train 35 line and the triple valve, will permit a restricted flow of air to the triple valve, in case an undesired emergency operation occurs in a triple valve, the construction being such that there may be a free and unrestricted flow 40 from the triple valve toward the train line, when a legitimate reduction occurs in the train line.

With the above and other objects in view, which will appear as the description proceeds, the invention resides in the combination and arrangement of parts and in the details of construction hereinafter described and claimed, it being understood that, within the scope of what is claimed, changes in 50 the precise embodiment of the invention shown can be made without departing from the spirit of the invention.

Figure 1 shows in longitudinal section, a device constructed in accordance with the 55 invention; Figure 2 is a transverse section

wherein parts are broken away; and Figure 3 is a diagrammatic plan showing the device forming the subject matter of this application in relation to sundry standard parts of an air brake equipment. 60

The numeral 1 marks a portion of a train line of an air brake system. The triple valve appears at 2. A conduit 3 forms communication between the triple valve 2 and the train line 1. The device 4 which forms the 65 subject matter of this application is interposed in the conduit 3. The conduit 3 includes a pipe 5 extending between the device 4 and the triple valve 2, and a pipe 6 extending between the device 4 and the train 70 line 1.

The numeral 7 denotes a casing including a body 8 having a nipple 9 receiving the pipe 6, and having a nipple 10 receiving the pipe 5. The body 8 has a neck 11, the end of 75 which forms a valve seat 12. A partition 14 extends entirely across the body 8 and divides the interior of the body into a passage 15 communicating with the pipe 6 and a passage 16 communicating with the 80 pipe 5. The partition 14 is flush, at its edge, with the periphery of the neck 11. The neck 11 is supplied with an outstanding flange 17 carrying ears 18 supporting a pivot member 19 passing through the neck 21 of a valve 85 20, the valve thus being hingedly mounted, and being adapted to rest on the end of the neck 11 and on the edge of the partition 14.

The casing 7 comprising a cap 22 having a 90 flange 23 cooperating with the flange 17 of the body 8. A gasket 24 is interposed between the flanges 23 and 17. Securing elements 25 connect the flanges 23 and 17. One wall of the cap 22 is provided with 95 a resilient buffer 26, acting as a stop for the valve 20, when the valve swings to an open position.

The space within the cap 22 constitutes a chamber 27. A port 28 in the valve 20 establishes communication between the chamber 27 and the passage 16. A port 29 is located in the neck 11 and establishes communication between the passage 15 and the chamber 27, independently of the valve 20. 105

In the event of an undesired emergency operation of the triple valve 2, the pressure in the train line 6 will be communicated to the triple valve by way of the passage 15, the port 29, the chamber 27, the port 28 and 110

the passage 16, thereby creating an increase of pressure at the triple valve 2 and releasing the brakes of the particular car which has been subjected to an undesired emergency application. There will be, however, no sudden reduction in the train pipe 6, since the ports 29 and 28 are of restricted cross section and the brakes of the other cars will not be set.

10 When there is a legitimate reduction in the train pipe 6, for the purpose of applying the brakes, the reduction will be communicated to the chamber 27, by way of the port 29, thereby permitting the valve 20 to open, 15 under the pressure in the passage 16 and the pipe 5, there being, under such circumstances, a substantially unrestricted flow from the pipe 5 and the passage 16, into the passage 16 and the train pipe 6, over 20 the edge of the partition 14.

Having thus described the invention, what is claimed is:—

1. In a device of the class described, a 25 casing provided with a chamber and having a partition defining passages; and a valve hingedly mounted in the casing between the chamber and the passages, the valve having a restricted port establishing communication between one passage and the chamber, the casing having a restricted port establishing communication, independently of the valve, between the other passage and the chamber.

2. In a device of the class described, a 30 casing provided with a chamber and having

a neck projecting into the chamber, the casing having a partition disposed transversely of the neck and defining passages; and a valve hingedly mounted in the casing between the chamber and the passages, 40 and seating on the neck, the valve having a restricted port establishing communication between the chamber and one passage, the neck being provided with a restricted port, independent of the valve, and establishing 45 communication between the chamber and the other passage.

3. In a device of the class described, a 50 casing comprising a body having a neck provided with an outstanding flange, there being a partition in the body and in the neck, the partition defining passages; a cap secured to the flange and forming a chamber; and a valve hingedly mounted on the flange and cooperating with the neck and with the partition, the valve being supplied 55 with a restricted port forming a communication between one passage and the chamber, the neck being supplied with a restricted port establishing communication, independently of the valve, between the other passage and the chamber.

In testimony that I claim the foregoing as my own, I have hereunto affixed my signature in the presence of two witnesses.

MICHAEL H. RYAN.
